DESIGN FOR A MOTOR SCOOTER

Harry A. Shaffer, Minneapolis, Minn.

Application July 20, 1945, Serial No. 120,834

Term of patent 7 years

(Cl. D90—8)

To all whom it may concern:

Be it known that I, Harry A. Shaffer, a citizen of the United States, residing at Minneapolis, in the county of Hennepin and State of Minnesota, have invented a new, original, and ornamental Design for a Motor Scooter, of which the following is a specification, reference being had to the accompanying drawing, forming part thereof.

Referring to the drawing:

Fig. 1 is a top plan view of a motor scooter showing my new design;

Fig. 2 is a side elevational view;

Fig. 3 is a front elevational view; and

Fig. 4 is a rear elevational view thereof.

I claim:

The ornamental design for a motor scooter, substantially as shown.

HARRY A. SHAFFER.
